FIG. 1.

FIG. 2.

FIG. 3.

FIGURE 1 is a front view of my safety start-stop control switch.

FIGURE 2 is a side view of the design shown in FIGURE 1.

FIGURE 3 is a perspective view of my safety start-stop control switch design.

The dominant features of the design reside in the portions shown in full line in the drawing which are further characterized by the raised appearance of the knob above the face plate as best seen in FIG. 3.

I claim:

The ornamental design for a safety start-stop control switch, as shown and described.
